UNITED STATES PATENT OFFICE.

STEPHEN H. BROOKS, OF CLEVELAND, OHIO.

FIRE-EXTINGUISHING INLET FOR FUEL-TANKS.

1,307,614.

Specification of Letters Patent. Patented June 24, 1919.

Application filed November 2, 1917. Serial No. 199,874.

To all whom it may concern:

Be it known that I, STEPHEN H. BROOKS, a citizen of the United States, residing at Cleveland, in the county of Cuyahoga and State of Ohio, have invented certain new and useful Improvements in Fire-Extinguishing Inlets for Fuel-Tanks, of which the following is a specification.

My invention relates to improvements in fire extinguishing inlets for fuel tanks and it more especially appertains to the special features pointed out in the annexed claims.

The purpose of my invention is to provide a form of flush inlet that is adapted for use on large storage tanks containing inflammable materials that will not be put out of service by explosions, etc., which tear off the roof of a tank and if not powerful enough to throw the roof to a distance will cause it to drop back and break off any inlet pipes, etc., that may project into the tank thus instantly putting an extinguishing system so equipped out of commission; to provide inlets which will distribute the extinguishing solution in separate horizontal layers; and that can be readily installed on old as well as new tanks without great expense or difficulty.

With these and other ends in view I illustrate in the accompanying drawing such instances of adaptation as will disclose the broad features without limiting myself to the use of only such specific details as are shown.

Figure 1—is a diagrammatic plan view exemplifying an arrangement of feeding connections that may be used to supply the pipe outlets whose exits serve the inlets of the tank.

Fig. 2—is a diagrammatic elevation illustrating the approximate vertical location of the inlets in the tank wall.

Fig. 3—is an inside elevation of an inlet secured in the tank wall.

Fig. 4—is a plan view in section of a semi-flush inlet.

Fig. 5—is a similar view to Fig. 4 of a flush inlet.

Fig. 6—is a vertical section of Fig. 4.

Fig. 7—is a vertical section of Fig. 5.

Fig. 8—is an elevation of a specially headed bolt.

Fig. 9—is a detached elevation in section of a part of an independent assemblable unit.

In practically carrying out my invention

the inlets 3 are placed in openings made in the side walls of tanks 1. These openings approximately fit the shoulders 19. Each of the inlets 3 is provided with a flange 8 and each of the flanges has ears 20 to accommodate fastening bolts 14 or 18. The body portion 9 extends outwardly forming a circularly shaped wall that has a beveled face 10 on the outside inner face against which a cap 11 abuts. These caps have ears 21 through which bolts 14 or 18 pass and control openings into which short feed pipes 4 are secured. The feed pipes 4 are supplied by pipes 5 and these in turn may be connected to main pipe 6. It is of course immaterial as to what specific arrangement of feed pipes and connections are employed as these may be varied at will to suit whatever practical exigencies may arise.

The inlets 3 as shown in Fig. 4 are held in place by bolts 14 provided with specially beveled heads that slope downward at 15 as shown in Fig. 8 so that there is no abrupt projection against which any falling roof 2 might strike and shear off the heads. Nuts 16 threaded on bolts 14 or 18 abut ears 20 and serve to hold inlets 3 in place against tank walls 1. Nuts 17 threaded onto bolts 14 hold ears 21 and caps 11 in place. The slots 7 may be beveled inwardly or outwardly as desired according to the specific modification of the fire extinguishing mist that is desired.

Whenever flush bolts are used they are threaded into tank walls 1 and have heads 22 which abut ears 21. Nuts 16 threaded on these bolts serve the same purpose as when they are placed on bolts 14. The slots 7 through which the fire extinguishing solution is expelled are narrow and are placed horizontally—about parallel with the level of the contents of tanks 1. By reason of this disposition of the slots the extinguishing solution is ejected in a number of horizontal layers as it leaves the outlets, thus assisting in more rapidly forming an extinguishing "blanket" over the burning contents. To further assist in the most efficient distribution of the solution the forward wall 105 of the inlets is curved spherically as shown in Figs. 4 to 7 inclusive. The ends of the slots are beveled so that the solution will be spread sidewise as much as possible. The object is to cause the delivery of the solution to be made far enough on each side so as to about reach an adjacent inlet on each

side. This insures that the material ejected from adjacent inlets will overlap and thus more effectively envelop the fire area with the extinguishing agent.

5. If desired I form the inlets as independent assemblable units as shown in Fig. 9 wherein shoulders 23 are formed on the bodies 9, 9^a and 9^b adjacent the ears 20 to receive bolts 22 to hold cover 12 attached to 10 the body independently of fastening bolts 25 by which the unit is held attached to the tank wall.

The fire hazard in storage tanks containing fuel oils and other highly inflammable 15 materials is very large even when extinguishing systems are installed because these depend on projecting pipes, etc., or supported pipes within the tank to support the outlet ends of such pipes. The reason for this extra hazard lies in the fact that when an 20 explosion occurs in a tank it is seldom of sufficient force to blow the tank roof to a distance so as not to fall on the tank as it descends. On the contrary the greater number 25 of such explosions are only of sufficient force to detach the roof at its outer edge from the body of the tank to form a vent and raise it straight up into space so that as it descends the edges are likely to shear off any projecting parts, pipes, etc., that may extend inwardly from the tank wall. With my invention such a contingency is entirely eliminated and the efficiency of the system is not lowered whatever happens to the tank roof.

35. The proportion of the slot widths of the inlets to the rest of the structure, instanced in the drawing, is not to be interpreted as a limitation. The determining ratio is any dimension which will cause the fire extinguishing solution under pressure to be expelled in a finely divided state as a mist to 40 form an oxygen excluding blanket which will almost instantly extinguish the fire. These terminal fittings having the delivery 45 slots are placed in openings of the tank wall and are attached to pressure pipes which are known as outlets of the pipe system, the fittings being known as inlets with respect to the tank.

50. The device is simple in construction, positive in operation, economical to manufacture, and easily applied thus combining very valuable features to produce a device whose practical features are obvious.

55. What I claim is,

1. In fire extinguishing systems, a tank for inflammable materials, a series of inlets placed in the wall of such tank above the

contents thereof said inlets being free from abrupt projecting parts within the tank, a 60 delivery chamber formed within each of the inlets, a spherical shaped delivery wall dividing the chamber from the inside of the tank, and parallel openings in such wall.

2. In fire extinguishing systems, a tank, 65 an extinguishing inlet provided with a main body portion having fastening projections by which it is secured in an opening of the wall of the tank, a curved exit facing the interior of the tank, openings through the 70 curved part, a removable cover placed on the inlet accessible from the outside of the tank, and means for holding the parts in assembled relation.

3. A tank for inflammable materials, an 75 extinguishing inlet attached thereto provided with a main body comprising a spherical wall, parallel exits leading through such wall, a cover to close the open side of the body to form an inclosing chamber, an inlet 80 to such chamber, and means for holding the parts in assembled relation while attached to the tank.

4. A tank for inflammable materials having 85 openings through its wall, restricted inlets placed in such openings so that the adjacent edges of the tank wall are substantially flush with the coöperating edges of the inlets, and means connected therewith for holding the inlets attached to the tank. 90

5. A tank for inflammable materials, a series of inlets in the tank wall spaced apart and encircling said tank, means for supporting the same in openings of the tank wall approximately flush with said wall, a pressure pipe leading to the inlets, the said inlets being so spaced in relation to the pressure within the pressure pipe that the area of activity of adjacent inlets will overlap so as to cause an envelopment of any fire within the tank by an extinguishing agent, under pressure in said pipe. 100

6. In fire extinguishing systems, a tank for inflammable materials having a series of openings through its walls above the level of its contents, removable flanged inlets in such openings, means for attaching the same to the tank from the outside so as to leave no abrupt protruding parts of the inlet extending into the tank, restricted apertures leading into the tank formed in each inlet, and means for connecting all the inlets to a pressure system common to all the inlets. 105

In testimony whereof I affix my signature.

STEPHEN H. BROOKS.
